UNITED STATES PATENT OFFICE.

JAMES A. CIVIS, OF CHICAGO, ILLINOIS, ASSIGNOR TO TITCHENER-DIEHL COMPANY, OF CHICAGO, ILLINOIS, A CORPORATION OF ILLINOIS.

CURTAIN-ROD BRACKET.

Application filed February 15, 1923. Serial No. 619,111.

To all whom it may concern:

Be it known that I, JAMES A. CIVIS, a citizen of the United States, and resident of Chicago, in the county of Cook and State 5 of Illinois, have invented certain new and useful Improvements in a Curtain-Rod Bracket, of which the following is a specification.

My invention relates to curtain fixtures 10 and particularly to a curtain rod bracket having novel and advantageous features.

In the device of my invention I employ a curtain rod of well-known shape and of so-called flat form. These rods consist of 15 a vertical web and marginal flanges in the form of beads. In my construction the flanges are flattened at the terminal points of the rod and the flattened portion is rebent to provide a hook.

20 The bracket which I employ is intended to interlock with a rod shaped as described and to securely hold the same against movement in any direction except in an upward oscillating direction, i. e. the reverse 25 of the movement by which the parts were engaged. The particular object in the improved design is to lessen the manufacturing cost of the associated parts and to increase the strength and rigidity of the assembly.

The invention will be more readily understood by reference to the accompanying drawing, wherein:

Figure 1 is a plan view of a curtain rod 35 and a pair of brackets constructed in accordance with my invention;

Figure 2 is an elevation partly in section on the line 2—2 of Figure 1;

Figure 3 is a side elevation of the bracket 40 which I employ;

Figure 4 is a sectional view on the line 4—4 of Figure 2;

Figure 5 is a perspective view of the bracket; and

45 Figure 6 is a perspective view of a modified form of bracket in which two curtain rods may be accommodated.

Referring more particularly to the drawings, it will be seen that the bracket of my invention is intended to be secured by suitable screws to a window casing 10 and to support a rod having a portion 11 parallel with the casing and angularly disposed end portions 12 at right angles to the casing.

50 The rod is preferably of so-called flat con-

struction comprising a web 13 and flanges 14. At the terminal portions of the rod, the flanges 14 are flattened, the material compressed vertically and the flat portions partially united by welding as described 60 in my copending application, Ser. No. 562,061, filed May 19, 1922.

The flattened portion is then rebent to form a hook 15 having a curved edge 16. The rod is, by reason of the construction 65 described, relatively stiff and strong at this point. The bracket of my invention comprises a fastening plate 17 having a right angle projection or ear 18 thereon. On the upper edge of the ear or lug is an in-turned hook 19 located near the junction of the projection with the plate. The width of the hook is merely sufficient to accommodate the flattened portion of the rod and the spacing of the hook away from the fastening plate is merely sufficient to accommodate the hook 15 of the rod therebehind. On the lower edge of the projection 18 is an up-turned hook 20 located at the outer 70 end of the projection. Both the hooks are 75 located on the same side of the projection, the hook 20 being preferably wider than the hook 19 in order to accommodate the full width of the flat rod. In the assembly 80 views it will be noted that the rod rests 85 securely on the bottom hook and engages against movement in two directions with the top hook. This provides a very rigid construction and one in which there is no shearing force exerted by small parts. The bearing 90 between the rod and bracket is broad and there is no tendency toward tearing out or shearing any parts due to excessive strain. The curved end of the hook facilitates inter-engagement of the parts as will be apparent. 95

In the construction of Figure 6 provision is made for the support of two rods as required when an overdrapé is desired. The construction of the bracket is identical with that described except that two projections, 100 each having hooks, are provided.

Obviously the construction may be varied considerably without departure from the spirit of my invention and I do not wish to be limited except as indicated in the appended claims.

I claim:

1. In a device of the class described, the combination with a flat curtain rod having hook ends of a pair of brackets, each con- 110

sisting of a fastening plate and a right-
angularly projecting ear, said ear having
a laterally projecting lug on its top edge
near its inner end, and a second laterally
5 projecting lug on its bottom edge near its
outer end, the hook end of the rod being
adapted to engage said first-mentioned lug.

2. In a device of the class described, the
10 combination with a flat curtain rod the end
portions of which are flattened and bent lat-
erally to form a hook of a pair of brackets,
each consisting of a fastening plate and a
right-angularly projecting ear, said ear
15 having a laterally projecting hook on its
top edge near its inner end, and a second
laterally projecting hook on its bottom edge
near its outer end, the hook on the rod en-
gaging said first mentioned hook.

3. In a device of the class described, the
combination with a flat U-shaped curtain rod, 20
the ends of which are flattened and rebent
to form a hook, of a pair of brackets, each
comprising a fastening plate having an
angularly disposed projection, a down-
turned hook on the upper edge of the pro- 25
jection near its junction with said plate
and of a width to accommodate the flattened
portion of the rod and spaced away from
the plate sufficiently to accommodate the
rod hook therebehind, and up-turned hook 30
on the lower edge of the projection near its
free end, said latter hook being of a width
to accommodate the full width of the rod.

Signed at Chicago, Illinois, this 6 day
of February, 1923.

JAMES A. CIVIS.
